UNITED STATES PATENT OFFICE.

CHARLES I. FLORY, OF KAHOKA, MISSOURI.

CAMERA.

No. 845,864.

Specification of Letters Patent.

Patented March 5, 1907.

Application filed September 6, 1906. Serial No. 333,496.

To all whom it may concern:

Be it known that I, CHARLES I. FLORY, a citizen of the United States, residing at Kahoka, in the county of Clark and State of Missouri, have invented a new and useful Camera, of which the following is a specification.

This invention relates to photographic cameras; and its object is to provide a camera having a bed on which the box of the camera and a plate-receptacle are disposed, said plate-receptacle being removable.

Another object is to provide the camera-box with a spring-actuated door adapted to close the lens-containing end of the camera and which will automatically open whenever the plate-receptacle is removed from the bed.

A still further object is to provide a camera-box made up of separable sections adapted to be moved to position at right angles to the bed and capable of being drawn apart to extend the bellows of the camera.

Another object is to provide an extensible bed whereby the sections of the camera-box can be moved at desired distances from each other in order to secure a predetermined focal length.

Another object is to provide a novel table or runner on which the sections of the camera-box are mounted so as to partly rotate, thereby permitting the front and rear portions of the camera to be adjusted to any desired angle in relation to the longitudinal center line of the bed.

A still further object is to provide a bed or runner of this character made up of sections adapted to combine when the camera is closed to form a guide on which the complete camera-box may rotate to assume a position above and in alignment with or at right angles to the longitudinal axis of the bed.

Another object is to provide a lens-box which can be disposed entirely within or can be extended beyond the end of the bellows, so as to facilitate the adjustment of the camera to secure a desired focal length.

With the above and other objects in view the invention consists of certain novel features of construction and combinations of parts, which will be hereinafter more fully described, and pointed out in the claims.

In the accompanying drawings is shown the preferred form of the invention.

In said drawings, Figure 1 is a perspective

view of the camera folded, portions thereof being broken away to show interior parts, the latch being shown by dotted lines in one of its disengaged positions. Fig. 2 is a horizontal section showing the camera extended, a large portion of the bellows being removed and a small portion thereof being shown in plan view, parts of the bed and camera-box being broken away to show details thereunder. Fig. 3 is a bottom view with parts broken away, showing the camera partly extended. Fig. 4 is a plan view of the camera, showing the box in position prior to extending the bellows. Fig. 5 is an enlarged section on line $\alpha\alpha$, Fig. 3. Fig. 6 is a rear elevation of the camera-box. Fig. 7 is a front elevation of the lens-holder and the front end of the camera-box, the hinged door being removed and the central portion of the lens-box of the camera being removed. Fig. 8 is a plan view of the table on which the sections of the camera-box are mounted. Fig. 9 is a section on line $\gamma\gamma$, Fig. 8. Fig. 10 is a transverse section through the means for clamping the back section of the camera-box upon the bed when the bellows is extended. Fig. 11 is a detail view showing one means which may be employed for locking the bed-extending mechanism. Fig. 12 is a detail view showing the universal stop in elevation. Fig. 13 is a vertical transverse section through the front table and bed-section and showing the connections therebetween. Fig. 14 is a detail perspective view showing the notches and guard-plates in the top of the front box section for engagement by the hooks of the plate-receptacle. Fig. 15 is a vertical section through the upper portion of the plate-holding frame and its connections, and Fig. 16 is a side elevation of a portion of said frame.

Referring to the figures by characters of reference, A is the main section of the bed of the camera, the same consisting of parallel side strips 1, connected at one end by an end strip 2 and adjacent the other end by one or more bottom strips 3. Each side strip has an upper groove 4 and a lower groove 5 extending throughout the length thereof, said grooves being parallel. An angular supporting-bracket 6 is secured to the central portion of the end strip 2, and one end of a guide-strip 7 is seated therein and is engaged by a screw 8, which is preferably swiveled within

- the end strip 2, so that by rotating the head 9 of the screw the guide-strip can be moved longitudinally in either direction. This guide-strip is arranged equidistant from and parallel with the side strips 1 and is provided in its upper face with a dovetail groove 10, which extends throughout the length of the guide-strip and is for the purpose hereinafter described.
- 10 A shaft 11 is journaled within the bottom strip 3 and is provided at one end with a head 12, whereby the same may be readily rotated. Any suitable means may be utilized for holding this head and its shaft against rotation.
- 15 In the drawings I have shown a rounded plate 13 surrounding the outer end of the shaft close to the head, and a locking-plate 14 is pivoted to one of the side strips 1 and has one edge sharpened, as at 15, so that the 20 plate can be forced downward between the head 12 and the plate 13 and act as a wedge. An extension 16 is formed upon the locking-plate to act as a finger-piece to facilitate the actuation of said plate. Although this particular means for locking the shaft has been 25 shown and described, it is to be understood that various other well-known means—such as pawls, ratchets, &c.—may be used in lieu thereof, such a construction being so obvious 30 that illustration and detailed description thereof is deemed unnecessary. A small gear 17 is secured to the shaft 11 near each end and projects a slight distance above the bottom strips 3. Slidably mounted between 35 the side strips 1 of the main section A of the bed is the intermediate section B of said bed. This section is made up of parallel side strips 18, having guide-cleats 19, arranged longitudinally upon their outer faces and which project into and are adapted to slide within the 40 lower grooves 5 in the sides of the main section A. These side strips 18 have their upper faces disposed just below the upper grooves 4, and both of the side strips 18 are 45 connected at their ends by cross-strips 20. Racks 21 are arranged longitudinally upon the inner faces of the side strips 18 and are constantly engaged by the gears 17 on shaft 11. A groove 22 is formed longitudinally 50 within the inner face of each side strip 18 and extends from end to end thereof, and hinged to the front cross-strip 20 of the intermediate section B is an end door 23, having recesses 24 formed in the ends thereof. By providing 55 these recesses 24 the door can swing between said strips 18 and close to the end of the section B. A reinforcing-strip 25 is secured to the side strips 18 adjacent the centers thereof, and the upper face of the strip is 60 preferably flush with the lower walls of the grooves 22.
- Slidably mounted between the side strips 18 of the intermediate section B is the top or end section C of the bed. This section consists of side strips 26, having cleats 27, which

are adapted to travel in the grooves 22, and these side strips are connected by end strips 28 and 29 and by an intermediate strip 30. The end strip 28 has a rounded recess 31 therein, into which one or more fingers of the operator may be placed for the purpose of sliding section C longitudinally within the section B. The end strip 29 is disposed back from the front ends of the side strips 26, and said ends of the side strips are reduced in 75 width, as shown at 32. Clamping-plates 33 are arranged upon the side strips 18 of the section B near their front ends and are adapted to overlap the side strips 26 of section C. Screws 34 extend through these 80 clamping-plates into the side strips 18, and by tightening them the plates 33 will bind on the side strips 26 and lock section C in any position to which it may be adjusted in relation to the section B. A table D is disposed 85 above the front portion of the bed-section C and consists of supporting-strips 35 and a top 36, said top having a recess 37 in its rear end. A semicircular T-rail 38 is suitably secured upon the table-top 36 and is concentric with 90 the recess 37. A groove 39 extends across the upper face of the T-rail at a point to one side of the center thereof.

A table E is slidably mounted on the guide-strip 7, and its side edges fit within the upper 95 grooves 4 of the side strips 1. This table has a forwardly-extending tongue 40, which is adapted when the bed is closed to be seated within the recess 37 in the table D. A curved L-shaped rail 41 is secured upon this tongue, 100 and a semicircular T-rail 42 is secured on the table E in such position that when the two tables are brought together the rails 38 and 42 will form a circular track, and the rail 41 will form an inner concentric semicircular 105 track. A guide-strap 43 is fastened to the tongue 40 and extends under guide-strip 7, so as to support said guide-strip. The rail 42 has a groove 44 extending thereacross at one side of the center thereof. A plate 45 projects rearwardly from the table E, and a clamping-plate 46 is slidably mounted within the groove 10 in guide-strip 7 and has a stem 47 extending from said groove and through the plate 45, where it is engaged by a thumb-nut 48. Obviously by turning this nut the plate 46 will be drawn upward against the upper wall of the groove 10 and will clamp the plate 45 upon the guide-strip 7, thereby locking the table E in any position to which it 110 may be adjusted.

One of the side strips 26 of the bed-section C has a universal stop 49 in the form of a strip which is pivoted, as at 50, to the side strip 26 and is adapted to be normally supported in a horizontal position by a stop-lug 51. A notched plate 52 is secured to the side strip 26, and as the strip 49 is of spring metal the same will spring into the notch in this plate when said strip is swung into an upright posi- 115 120 125 130

tion. When the camera is closed, this stop-strip 49 is in position between the rear end 2 of the bed-section A and the table E. Obviously by swinging the strip 49 upward, as 5 shown in Fig. 12, the rear table E cannot be slid backward any farther than the strip 49, and by pulling forward on the bed-section C and the table D secured thereto the stop-strip 49 will be carried forward into contact 10 with the rear table E, and therefore limit the forward movement of the front table. By swinging the stop-strip 49 into a horizontal position it will not interfere with the longitudinal adjustment of the table.

15 A pivot-pin 53 extends from the table E at the point which constitutes the center about which the rails 41 and 42 are disposed. Mounted on this pin is the rear section F of the camera-box. This rear section consists 20 of a base 54, sides 55, and top 56, said sides and top being provided with doors 57, whereby light may be prevented from entering the section F after a plate-holder has been placed in position therein. A spring 58 is secured 25 upon the base 54 and has a lug 56' extending downward therefrom and adapted to ride upon the rail 42. When the base assumes a position at right angles to the bed-section A, this lug will spring into the groove 44. In 30 order that the lug may be raised from the groove, so as to permit the section F to be swung to another angle in relation to the bed, a finger-piece 60 is connected to the spring 58 and projects beyond the base 54. A screw 35 61 is threaded within the base and has a lever 62 secured to it. By swinging this lever in one direction the end of the screw may be caused to bind upon the table E, so as to hold the section F at any angle other than a right 40 angle to which it may be adjusted in relation to the bed. Base 54 has a tongue 63 extending forward from it, and this tongue is provided with a curved L-shaped rail 64, which extends under the rail 41 and is concentric 45 therewith. Concentric semicircular L-shaped rails 65 are secured upon the bottom of the base 54 and are oppositely disposed, so as to extend under the opposite edges of the rail 42. A notch 66 is formed in one end of 50 the top 56 and has a guard-plate 67 extending thereover. A tongue 68 extends beyond this end of the top 56, and a handle 69, preferably in the form of a strap, is fastened to the tongue. Arms 70 extend rearwardly from 55 the centers of the sides 55 of section F, and between these arms is pivoted a frame 71, to which one end of a bellows 72 is secured. Spring-catches 73 extend from the frame 71 and are adapted to engage a rear frame 74, 60 made up of separable sections 75 and 76, the outer one, 76, of which is connected to the inner by a spring-strip 77, so that the two sections 75 and 76 can be spread apart to permit the insertion of a plate-holder between them.

65 In order that the frame 71 and parts con-

nected thereto may be fastened at a desired angle, slotted strips 78 are pivoted to the lower portions of the sides of the frame and are adapted to be clamped to the sides 55 of the section F by means of clamping-screws 79.

70

The front end of the bellows 72 is secured within a frame 80, having parallel slots 81 in opposite sides thereof, and this frame is fitted within the front section G of the camera-box, it being held therein by means of thumb-screws 81', which extend from the front of the section G and through the slots 81. Guide-cleats 82 are formed upon the inner faces of the sides 83 of section G, and the frame 80 is mounted to slide between these 80 cleats and to be held in adjusted position by means of the thumb-screws 81'. The bottom 84 of section G has a recess 85 cut in the center of the rear thereof to receive the tongue 63 of the rear box-section F. Oppositely-disposed 85 concentric semicircular L-shaped rails 86 are secured upon the lower face of the bottom 84 and engage opposite edges of the rail 38.

The front of the section G has a large rectangular opening 87, and formed within this 90 front below the opening are slots 88 and 89. A lever 90 extends through the slot 88 and is secured to one end of a screw 91, which is threaded through the bottom 84 and is adapted to bear against the table D and secure the section G at any angle to which it may be adjusted in relation to the bed. A spring 91' is also secured to the bottom and has a lug 92 thereon, which is loosely mounted within the bottom and is adapted when section G is 100 moved to a desired position at right angles to the bed to spring into the recess or groove 39 and lock said section against further movement. A finger-piece 93 extends forward from the spring 91 and through the other slot 105 89. By lifting this finger-piece the lug 92 can be withdrawn from the groove 39, and the section G will therefore be free to rotate upon the rails thereunder.

The section G is not provided with a top, 110 but is adapted when the two sections F and G are brought together to be closed by a strip 94, extending forward from the top 56 of section F. The upper end of one of the sides 83 of the section G, however, has a notch or recess 95, provided with a guard-plate 96, said recess and guard-plate being similar to the recess 66 and the guard-plate 67 described in connection with the box-section F.

The front opening 87 within the section G 120 is adapted to be closed by a hinged door 97, provided with a spring 98, whereby the door will automatically open whenever released. This door is adapted to be held closed by means of a sliding bolt 99, mounted upon the front 125 of the section G and having a head 100 pivotally connected thereto and adapted to overlap one edge of the door. The bolt 99 has an extension 101 extending at right angles thereto and overlapping a spring-strip 102, 130

which is fastened to one of the sides 83 of the section G. This spring serves to hold the bolt normally withdrawn from engagement with the door 97.

5 The front face of the adjustable frame 80 is recessed, as shown at 103, to constitute a seat for a flange 104, extending around one end of a rectangular lens-box 105. This box is adapted to be projected into the front end 10 of the bellows, as shown in full lines in Figs. 1 and 2, or if it is desired to increase the focal length of the camera the box may be reversed, so that the lens therein will be disposed beyond the front face of the section G, as shown by dotted lines in Fig. 2. In order that the lens-box may be fastened in place, turn-buttons 106 are pivotally mounted within the recesses 103 and are adapted to overlap the flange of the lens-box, as shown particularly in Fig. 1. In order that these buttons will not interfere with the closing of the door 97, they may be disposed within recesses 107, as shown in said Fig. 1.

When the camera is not in use, the bed-sections A, B, and C are moved longitudinally, so that both of the sections B and C will be disposed entirely between the sides of the section A. The two sections F and G of the camera-box are in contact, with the strip 94 closing the top of the section G. The combined thickness of the two sections F and G is equal to the width of the bed-section A, and the two sections normally assume a position with their front and rear portions above the two sides 1, as shown in Fig. 1. When in this position, there is a sufficient portion of the bed left uncovered by the camera-box to permit a plate-holder receptacle to be supported by the bed. This receptacle 108 has been shown in Fig. 1 and consists of a suitable rectangular casing having blocks 109 extending downward from the bottom thereof and adapted to fit between the side strips 1 and the end strip 2 of the bed-section A, so as to prevent it from slipping out of position. The tongue 68 is adapted to extend over a recess in the top of the receptacle 108, and hooked straps 110 are fastened upon the top of the receptacle and are adapted to be seated within the notches or recesses 66 and 95, so as to hold the receptacle 108 securely connected to the camera-box. A notch 111 is formed within one face of the receptacle 108 and is adapted to receive the extension 101 of bolt 99. When the receptacle is placed in proper position upon the bed, as shown in Fig. 1, it forces the bolt 99 longitudinally, so that the head 100 thereof will overlap the door 97 and spring 102 will be tensioned. As soon, however, as the receptacle 108 is lifted off of the bed the tensioned spring 102 will slide the bolt 99 so that its head will be withdrawn from engagement with the door. A handle 112 is arranged upon the top of the receptacle 108, so that the same can be readily

lifted from or placed into position. A suitable number of plate-holders 113 may be arranged within the receptacle 108, as shown.

With the parts in the positions shown in Fig. 1, the operation of adjusting the camera into position for taking pictures is as follows: With one hand grasping the handle 69 the operator grasps the handle 112 with the other hand and lifts the plate-receptacle 108, so as to withdraw the hooks 110 from the notches 66 and 95 and the blocks 109 from engagement with the bed-section A. The plate-receptacle 108 can then be placed at any convenient point, and as soon as it is removed from the camera-box the tension-spring 102 is released and pushed outward on the extension 111 of bolt 99, thereby withdrawing the head 100 from engagement with door 97. The door will therefore automatically open and expose the shutter and lens-box. As will be readily understood, this door can be easily opened without removing the receptacle 108 simply by swinging the head 100 upon its pivot, as shown by dotted lines in Fig. 1. This is an important feature, because it permits the front of the camera-box to be quickly opened for the purpose of obtaining access to the shutter or lens. As soon as the door 97 has been opened by the first operation of removing the plate-receptacle the entire camera-box is swung into position at right angles to the bed, this movement being permissible in view of the fact that the rails on the bases of the two box-sections F and G will travel upon the T-rails on the tables D and E. As soon as the two sections F and G of the camera-box arrive in position at right angles to the longitudinal axis of the bed the lugs 92 and 56' will automatically spring into the notches 39 and 44 and lock the box-sections against further rotation. This completes the second operation involved in setting up the camera. If the universal stop 49 is employed, the third and final operation involved in setting up this camera consists in first swinging said stop into an upright position, so as to engage the notched plate 52, and then pulling the rear box-section F backward within the grooves 4 and upon the guide-strip 7 until the section comes into contact with the stop. It can then be locked by means of the clamping-plate 46 and the thumb-nut 48. Instead of extending the camera in this way the rear section F of the camera-box may be held stationary, while the intermediate section B is moved forward, and by turning the shaft 11 the end section C will be carried forward with the intermediate section, because the same is normally clamped in position within the intermediate section by means of the plates 33. Where a considerable focal length is desired, the rear section F of the camera-box can be drawn backward upon the bed 1 and secured to the rear end of the guide-strip 7 by means of the thumb-nut 48 in the

manner heretofore described. The clamping-plates 33 can then be released from engagement with the side strips of the end section C, and by placing the hand under the bed 5 and into the recess 31 in end strip 28 said bed-section C can be pushed forward, and will of course carry the front section G of the camera-box with it, thus partially extending the bellows 72. A still further extension of the camera-box can be obtained by unlocking the shaft 11 and rotating it so that the gears thereon will force the racks 21 longitudinally 10 and carry the intermediate section B, as well as the end section C, forward. When a desired extension has been secured, the shaft is again locked, so as to prevent the bed-sections of the camera-box from drawing together. Minute adjustments of the camera while extended may be secured by means of the screw 20 8, which engages one end of the guide-strip 7. By rotating this screw said guide-strip 7 and all parts connected to it will be moved longitudinally in a desired direction. Should the focal length of the extended camera be less 25 than that desired, the same can be increased by reversing the lens-box within the frame 80, as shown by dotted lines in Fig. 2. By releasing the lugs 61 and 92 from engagement with the rails thereunder the two box-sections 30 F and G of the camera may be swung into desired angles in relation to the bed for the purpose of securing certain results in photography, and these sections may be locked in these positions by swinging the levers 62 and 90 so as to cause screws 61 and 91 to bind on the 35 tables thereunder.

It is to be understood that, if desired, the receptacle 108 may be dispensed with and the bed-sections A, B, and C proportionately 40 shortened, so that when the camera is in its normal or closed position it will entirely cover the collapsed bed.

It is also to be understood that any suitable means may be employed for connecting 45 a tripod to the bottom strip 3 of the bed-section A. This strip is at all times approximately under the center of gravity, so that when the camera is extended it will be supported by the tripod without danger of tilting.

It is of course understood that when it is desired to close the camera the operation of opening it which has been described is merely reversed.

55 The lens-board 105^a must necessarily be reversible in the box 105, so that the lens and the shutter connected thereto will always extend to the front. It is also to be understood that the screw 8 engages the guide 7 in a plane below the slot 10, so that the full length of said slot may be utilized.

The invention herein described is advantageous because of the few essential parts embodied in its construction and because 65 these parts are so arranged as to secure the

greatest strength and the maximum degree of adjustment. Moreover, the invention is advantageous because of the few motions or operations required in order to get it ready for use.

70 While specific forms of rails for supporting the box-sections upon the tables have been shown and described, it is to be understood that any kinds of interlocking rails permitting rotation of the box-sections on the bed 75 without becoming detached may be substituted.

Each of the box-sections can be very easily detached by turning it one-half a revolution upon its rails, so that the semicircular rails 80 carried by the box will move out of engagement with the semicircular rails upon the table thereunder. After the rails have been disengaged in this manner the box-section can be lifted off of its pivot 53.

85 The camera-box may be either constructed as shown in the drawings or may consist of any kind of frames capable of holding the camera, bellows and accessories.

The box or combined frames may be of any 90 thickness desired without reference to the width of the bed, and by the term "box-sections" herein used it will be understood that I do not limit myself to the particular construction shown and described, but said 95 term is intended to cover any separable parts for holding the bellows, &c.

The preferred form of the invention has been set forth in the foregoing description; but I do not limit myself thereto, as I am 100 aware that modifications may be made therein without departing from the spirit or sacrificing the advantages thereof, and I therefore reserve the right to make such changes as fairly fall within the scope of the 105 claims.

What is claimed is—

1. In a camera the combination with a bed; of a camera-box pivotally and slidably mounted upon the bed, said box adapted to 110 assume a position in alignment with or at right angles to the longitudinal axis of the bed.

2. In a camera the combination with a bed; of a sectional camera-box rotatably 115 mounted upon the bed, said sections being adjustable from or toward each other longitudinally of the bed and adapted to assume a position in alignment with, or at right angles to the longitudinal axis of the bed.

120 3. In a camera the combination with a bed; of a camera-box rotatably mounted upon the bed and adapted to assume a position in the same plane therewith or at right angles thereto, said box consisting of separate sections, and means for independently adjusting the sections from or toward each other.

125 4. In a camera the combination with a bed; of a camera-box rotatably mounted 130

- upon the bed and adapted to assume a position in the same plane therewith or at right angles thereto, said box consisting of separate sections, means for independently adjusting the sections from or toward each other, and a bellows connecting the sections.
5. In a camera the combination with a bed; of a camera-box mounted to rotate upon the bed, said box consisting of separate sections adapted to assume a position in alignment with, or at right angles to the longitudinal axis of the bed, means upon each section for locking it at a predetermined angle to the bed, and a bellows connecting the sections.
- 15 6. In a camera the combination with a bed; of a camera-box rotatably mounted upon the bed and consisting of separable sections adapted to assume a position in alignment with, or at right angles to the longitudinal axis of the bed, a bellows connecting the sections, and means for automatically locking said sections at predetermined angles to the bed.
- 25 7. In a camera the combination with a bed; of a camera-box rotatably mounted upon the bed and consisting of separable sections adapted to assume a position in alignment with, or at right angles to the longitudinal axis of the bed, a bellows connecting the sections, means for automatically locking said sections at predetermined angles to the bed, and manually-operated means for securing said sections at predetermined angles to the bed.
- 35 8. In a camera the combination with a bed; of a camera-box rotatably and slidably mounted upon the bed, said box consisting of separable sections independently movable and adapted to assume a position in alignment with, or at right angles to the longitudinal axis of the bed, and a bellows connecting the sections and adapted to be inclosed thereby.
- 45 9. A camera comprising a bed, a camera-box rotatably and slidably mounted thereon, said box consisting of separable sections independently movable longitudinally of the bed and adapted to assume a position in alignment with or at right angles to the longitudinal axis of the bed, a bellows connecting and adapted to be inclosed by the sections of the box, one of said box-sections having a continuously-exposed face, and a closure therefor.
- 55 10. A camera comprising a bed, a camera-box rotatably and slidably mounted thereon, said box consisting of separable sections independently movable longitudinally of the bed, a bellows connecting and adapted to be inclosed by the sections of the box, one of said box-sections having a continuous y-exposed face, a closure for said face, a lock therefor, and means for automatically opening the closure when released from the lock.

11. In a camera the combination with a bed; of a rotatable camera-box slidably mounted upon the bed, said box consisting of separable independently-movable sections, and adapted to be disposed above and in alignment with or at an angle to the bed, a closure for one of the box-sections, a lock therefor, and a receptacle detachably mounted upon the bed and adapted to hold the lock in engagement with the closure.
- 75 12. In a camera the combination with a bed; of a camera-box rotatably mounted upon and adapted to move longitudinally of the bed, said box consisting of separable sections and adapted to lie in the same plane with or at an angle to the bed, a receptacle detachably mounted upon the bed, a closure upon one face of the camera, means for automatically opening the same, and a bolt for holding said closure when shut, said bolt being retained in locking position by the receptacle.
- 80 13. In a camera the combination with a bed, and a separable camera-box pivotally mounted upon the bed and adapted to lie in the same plane therewith; of a receptacle detachably mounted upon the bed, a closure upon one face of the camera-box, a lock for holding the closure when shut, and means for automatically releasing said lock from the closure, said lock being normally held in engagement with the closure by the receptacle.
- 85 14. In a camera the combination with a bed, and rails independently movable upon the bed and adapted to co-operate to form a circle; of a box-section mounted to travel upon each rail, said sections when together being simultaneously rotatable upon both rails and constituting a camera-box, and a bellows connecting the sections of the box.
- 90 15. In a camera the combination with a bed; of a sectional circular rail supported thereby, the sections of said rail being separable, a sectional camera-box mounted to rotate upon the circular rail, each rail-section constituting a support and guide for each box-section when spaced apart, and a bellows connecting the box-sections.
- 95 16. In a camera the combination with a bed; of a sectional box pivotally mounted upon the bed, and a bellows connecting and adapted to be inclosed by the sections of the box, said box being movable into position either in alignment with or at an angle to the bed.
- 100 17. In a camera the combination with a sectional extensible bed; of a sectional camera-box pivotally mounted upon two sections of the bed, said sections being independently movable with the bed-sections and adapted when together to rotate about a common center.
- 105 18. In a camera the combination with a sectional extensible bed; of a sectional circular rail, the sections of said rail being con-

5 nected to separate sections of the bed, and a sectional camera-box mounted to rotate upon the circular rail, the sections of said box being adapted to be engaged solely by, and movable with the rail-sections.

19. In a camera the combination with a sectional longitudinally-extensible bed; of a sectional circular rail secured upon the bed, the sections of said rail being secured to separate sections of the bed, and a sectional camera-box engaging and rotatable upon the circular rail, said box being adapted to assume positions in the same plane with the bed and at right angles thereto, the sections of said box being separately supported by, and independently movable with, the rail-sections when at right angles to the bed.

20. In a camera the combination with a sectional extensible bed; of tables carried by separate sections of the bed, semicircular rails thereon, said rails and tables being adapted to be brought together to form a circular rail, a box-section pivotally connected to one of the tables, a second box-section, rails thereon slidably engaging the rails on the other table, and means for locking the box-sections in desired positions upon the rails.

21. In a camera the combination with a sectional extensible bed; of tables carried by separate sections of the bed, semicircular rails thereon, said rails and tables being adapted to be brought together to form a circular rail, a box-section pivotally connected to one of the tables, a second box-section, rails thereon slidably engaging the rail on the other table, means upon each box-section for automatically locking said section in a predetermined position upon its rail, and manually-operated means for locking each box-section in a predetermined position.

22. In a camera the combination with a bed; of a camera-box-supporting device comprising separable tables, one of said tables having a recess, a tongue upon the other table adapted to be seated within the recess, oppositely-disposed curved rails upon the tables adapted to coöperate to form a circular rail, and a curved rail concentric with said rail and disposed upon the tongue.

23. In a camera the combination with a bed; of a camera-box-supporting device comprising separable tables, one of said tables having a recess, a tongue upon the other table adapted to be seated within the recess, oppositely-disposed curved rails upon the tables adapted to coöperate to form a circular rail, a curved rail concentric with said rail and disposed upon the tongue, and a camera-box section movably engaging the rail on the recessed table, said section having a recess therein, a second camera-section, a tongue extending therefrom and adapted to be seated in the recessed section, and rails upon said second section and its tongue for engag-

ing the corresponding rails on the table thereunder.

24. In a camera a bed comprising a main section, an intermediate section slidably mounted therein and adapted to extend therebeyond, an end section slidably connected to the intermediate section and adapted to extend therebeyond, and a sectional camera-box, one section of said box being connected to the main section of the bed and the other section of said box being connected to the end section of the bed said box-sections when together being rotatable about a common center. 70

25. In a camera a bed comprising a main section, an intermediate section slidably mounted therein and adapted to extend therebeyond, an end section slidably connected to the intermediate section and adapted to extend therebeyond, and a sectional camera-box, one section of said box being connected to the main section of the bed and the other section of said box being connected to the end section of the bed, said box-sections when together being rotatable about a common center. 80 85

26. In a camera a bed comprising a main section, an intermediate section slidably mounted therein and adapted to extend therebeyond, an end section slidably connected to the intermediate section and adapted to extend therebeyond, a sectional camera-box, one section of said box being adjustably connected to the main section of the bed and the other section of said box being adjustably connected to the end section of the bed, said box-sections when together being rotatable about a common center. 90 95

27. In a camera a bed comprising a main section, a guide-strip adjustably connected thereto, and disposed longitudinally therein, an intermediate section adjustably connected to the main section, means for actuating the intermediate section, an end section slidably connected to the intermediate section, and means for securing the sections in adjusted positions. 100 105 110

28. In a camera a bed comprising a main section, an intermediate section and an end section telescopically connected, means for adjusting the intermediate section longitudinally, means for locking the sections in adjusted positions, a guide-strip adjustably connected to and extending longitudinally of the main section of the bed, and a sectional camera-box, one section of said box being adjustably mounted on the guide-strip and the other section connected to the end section of the bed. 115 120

29. In a camera a bed comprising a main section, an intermediate section and an end section telescopically connected, means for adjusting the intermediate section longitudinally, means for locking the sections in adjusted positions, a guide-strip adjustably 125 130

connected to and extending longitudinally of the main section of the bed, and a sectional camera-box, one section of said box being pivotally and slidably connected to the guide-strip and the other section of said box being pivotally mounted upon the end section of the bed.

30. In a camera a bed comprising a main section, an intermediate section and an end section telescopically connected, means for adjusting the intermediate section longitudinally, means for locking the sections in adjusted positions, a guide-strip adjustably connected to and extending longitudinally of the main section of the bed, and a sectional camera-box, one section of said box being adjustably mounted on the guide-strip and the other section connected to the end section of the bed, and a stop adjustably connected to the end section of the bed and adapted to project into the path of one of the box-sections.

31. In a camera the combination with a bed; of a box comprising separable front and rear sections, and a bellows connecting said sections and adapted to be entirely inclosed thereby, said sections when together being rotatable about a common center.

32. In a camera a box comprising a front and a rear section, said sections being separable, a bellows connecting the sections, a closure for the front section, and a reversible lens-box detachably mounted within the front section and in rear of the closure.

33. In a camera the combination with a bed; of a sectional camera-box rotatably mounted upon the bed; said sections being separable when disposed at an angle to the bed, a plate-receptacle detachably mounted upon the bed, said receptacle and box being normally disposed above and in alinement with the bed, and a handle upon the box and extending over the receptacle.

34. In a camera the combination with a bed; of a sectional camera-box rotatably mounted upon the bed, said sections being separable when disposed at an angle to the bed, a plate-receptacle detachably mounted upon the bed, means upon said receptacle for detachably engaging the box, and a handle upon the box, said box and receptacle being normally disposed above and in alinement with the bed.

35. In a camera the combination with a bed; of a sectional camera-box rotatably mounted upon the bed, said sections being separable when disposed at an angle to the bed, a plate-receptacle detachably mounted upon the bed, means upon said receptacle for detachably engaging the box, a handle upon

the box, said box and receptacle being normally disposed above and in alinement with the bed, a closure upon the box, and a lock therefor, said lock adapted to be held in engagement with the closure by the receptacle. 65

36. In a camera the combination with a bed, a table adjustably mounted thereon, curved concentric rails upon the table, a camera-box, and rails upon said box engaging the rails on the table, said rails on the box being detachable from the table-rails when moved a predetermined distance thereon.

37. In a camera the combination with a bed comprising adjustably-connected sections; of a table, E, adjustably connected to one of said sections, a table, D, rigidly connected to another section, curved rails secured upon the tables, and box-sections rotatably mounted upon the respective rails, said sections being detachable from the rails 80 when rotated a predetermined distance thereon.

38. A camera comprising a bed; a box movably mounted thereon, a closure connected to the box, a lock for securing it in closed position, and a receptacle detachably mounted upon the bed and adapted to hold the lock in engagement with the closure.

39. In a camera, the combination with a bed; of a camera-box upon the bed, a closure connected to the box, means for automatically opening said closure, a lock for the closure, and a receptacle detachably mounted upon the bed and adapted to hold the lock in engagement with the closure. 95

40. In a camera, the combination with a bed; of a box mounted thereon, a receptacle detachably mounted on the bed, a closure upon one face of the box, means for automatically opening the same, and a bolt for holding the closure when shut, said bolt being retained in locked position by the receptacle.

41. In a camera, the combination with a bed, of a sectional circular rail, said sections being separable, and a sectional camera-box mounted to rotate upon the rail and movable with the respective sections. 105

42. In a camera, the combination with a box; of a closure upon said box, and a reversible lens-box detachably mounted within the camera-box and in rear of the closure.

In testimony that I claim the foregoing as my own I have hereto affixed my signature in the presence of two witnesses.

CHARLES I. FLORY.
